SONIC SPRAY DRYING

Caperton B. Horsley, Stamford, Conn., and Harold W. Danser, Jr., Belmont, Mass., assignors to Ultrasonic Corporation, Cambridge, Mass., a corporation of Massachusetts

Application July 29, 1947, Serial No. 764,384

2 Claims. (Cl. 109—48)

1

Our invention relates to improvements in the art of spray drying.

In connection with many industrial processes spray drying is utilized to remove moisture from wet substances such for examples as soaps, pharmaceuticals, foods to be dehydrated, resins, etc.

As usually practiced, the material to be dried is sprayed through an atomizing nozzle into a large tank through which hot dry gas is passed. Some of the dried particles fall out by gravity and are collected, other are separated from the gas in cyclone separators, while the smallest ones pass off into the atmosphere. Inasmuch as the drying action of the stream of hot gas is much more efficient when the treated material is in finely divided form, spray drying has become an important and widely adopted technique.

Our invention is based upon the discovery that sound waves can advantageously be used to improve the efficiency and economy of spray drying, and, in some cases, to improve the quality of the final product.

The rate at which a wet particle loses moisture depends to an important degree upon its diameter, its speed relative to the surrounding air, and the temperature and relative humidity of the air. The most important object of our invention is to improve spray drying by employing sound waves to increase the relative speed between the hot gas and the wet particles.

Although very fine particles dry more readily than larger ones, it often happens that the end product is disadvantageously affected by the presence of fines. For example, soap powders containing very small soap particles are undesirable because the fines cause sneezing. In many instances the optimum product is one in which the particle sizes vary only through a small range. Another object of our invention is to improve spray drying by producing dried particles of substantially uniform size, through the agglomerating action of sound waves on the wet particles.

Furthermore, in conventional spray driers significant amounts of the substance treated are often carried off as fines too small for separation by cyclones or comparable apparatus. This loss constitutes not only a waste but a public nuisance in areas surrounding the drier. Another object of our invention is to provide a simple, efficient method for eliminating these and other losses in spray driers.

One problem ordinarily encountered in spray drying is the fouling of the drier due to material depositing on the walls of the tanks. The ex-

2

tent of deposition depends somewhat on the nature of the material being dried. In many cases, however, it has been found necessary periodically to close down the drier in order to remove these deposits from the walls. Furthermore, these deposits frequently constitute a fire hazard. Another object of our invention is to improve the efficiency and safety of spray drier operation by preventing fouling.

The most important feature of the invention resides in applying sound waves at frequencies and intensities sufficient to develop greatly increased velocities between the droplets or wet particles and the hot gas, thus, in effect, flowing a much greater volume of drying gas over each particle.

Obviously, the method here discussed is applicable to the evaporation of various liquids into gases of many different chemical compositions. For convenience we shall refer generally to water evaporating into hot dry air. Those skilled in the art will readily appreciate the factors involved in adapting the method for use with other materials.

In carrying out the method of our invention we spray the material to be dried into the top of a cylindrical tower or tank and simultaneously pass through the tank a stream of hot dry air. The result is that an aerosol is formed in the tower, including wet particles or droplets of various sizes depending upon the nature of the substance to be dried and upon the design of the spray nozzles. Through the medium of a powerful sound wave generator, there is maintained inside the tower a mean sound wave intensity of preferably 150 decibels or db above zero reference level, or higher, where zero reference level is understood by convention to be 0.0002 dynes/cm.² root mean square pressure. We have found that a modified form of the variable frequency sound wave generator disclosed in the copending application of C. B. Horsley et al., Ser. No. 722,240 filed January 15, 1947, and now Patent No. 2,535,680, provides a satisfactory source of sound at frequencies between 1 and 100 kc., which range appears to be the most suitable for carrying out the method of our invention.

The generator develops an intense sound field within the drying tank, and the sound waves act to develop large velocities between the drying gas and the wet particles. Consequently the evaporation rate is significantly increased. It follows that in spray driers where the humidity of the gas leaving the drier is significantly lower than 100%, but where the final product has been satisfactorily

dried, the use of sound waves and the consequent improvement in evaporation rate will make it possible to do the same work with a lesser flow of gas through the system, or at a lower temperature, or both. In this case, the relative humidity of the exit gases will be closer to 100% for the same flow of exit water vapor. Conversely if the inlet temperature and volume flow were left the same, the amount of material spray dried in the same tank could be increased.

We have found that another important advantage flows from the practice of our novel method. It can be calculated that a given quantity of wet particles must remain for a certain period in the drying gas under normal conditions. This time factor largely determines the height of the drying tower. The evaporation of the moisture is so speeded up in our method that the time factor is greatly reduced. Therefore, we can employ a much smaller drying tower than has been formerly used to dry comparable quantities of material. That is to say, we are able to increase the dry product output per cubic foot of drying tank.

Furthermore advantage may be taken of the agglomerating effect of sound waves acting in an aerosol. For example where the size of the dried particles is ordinarily undesirably small, we may select a frequency such that small wet particles agglomerate before drying—resulting in cohesive dried particles of satisfactorily large diameter. The final product will contain particles whose range of size is therefore reduced. Where the problem relates more to separation of the dried particles from the gas, we may select a frequency at which the dried particles will at least temporarily agglomerate to sizes large enough to facilitate separation in conventional cyclone separators or the like.

Finally, one action of the sound waves, as will be more fully discussed, is to strip deposited material from the walls of the drier, thus enabling continuous operation of the equipment and preventing clogging or fouling. Here the properties of the treated material may affect the degree to which sonic stripping becomes effective.

The selection of the amount of acoustic energy to be developed in the drier by the generator is a straightforward matter, since both evaporation and agglomeration effects vary with the intensity above an effective threshold which varies somewhat with different conditions but lies in the neighborhood of 150 db mean sound pressure above zero reference level.

The selection of an operating frequency is a much more complicated matter. It must first be decided whether agglomeration of either the wet or dry particles is desired. If no agglomeration is required, the frequency will be selected from the high end of the range. At relatively high frequencies the gas will move in response to sound wave forces but the particles will not be significantly affected. The result is that the gas will flow by the particles and the relative velocity between the particles and the gas is at a maximum. As the frequency is reduced there is a range in which the gas and the finer, and drier, particles are moved in response to sound wave forces but the larger particles are relatively stationary. At still lower frequencies the differential velocities between particles of differing mass-to-drag ratios become maximum. Consequently the agglomerating effects of the sound waves depend primarily on the distribution of particle sizes in the aerosol in the area in ques-

tion. This distribution varies as the drying proceeds, with the result that a frequency may be selected at which maximum agglomeration of undried particles will take place or by choosing a different frequency the bulk of the agglomeration will be among dried particles.

In many cases, if wet particles are agglomerated the solid nuclei will be more cohesive when dried than if the agglomeration operates on particles already dried, although wet agglomeration may slow down the drying process. These factors serve to determine the choice of agglomerating conditions mentioned above.

The method of determining the optimum frequency range for each installation will be further evident from a reading of our copending application Ser. No. 696,628, filed September 12, 1946, and now Patent No. 2,535,679, for Process of Agglomerating Aerosols. It will appear that the proper frequency for agglomerating wet particles will be lower than that for the agglomeration of dried particles, since in general the wet particles will be heavier than the dry particles. It must be pointed out, however, that there can be no sharp demarcation between the agglomeration of wet or dry particles. That is to say, a frequency selected to agglomerate wet particles will inevitably bring about some agglomeration among dried particles and vice versa.

As an example, if the particle size range of wet particles extends from 1 to 30 microns, it will be found that at 3.5 kc. considerable agglomeration will take place. It is the differential velocity between the air and the particles which controls evaporation but the differential velocity between particles of different sizes which probably controls agglomeration. Consequently it is possible simultaneously to agglomerate the wet particles and also to evaporate the moisture from them. In that case the overall size of the particles is progressively diminished due to evaporation but the solid nuclei are continuously increased because of agglomeration. Obviously, the production of relatively dry agglomerates facilitates the subsequent separation of the solids from the gas. Indeed, our method may be practiced to render possible the recovery of materials often lost in the form of particles so fine as to be unresponsive to the action of cyclone separators or the like.

The practice of our method is not confined to the drying of materials hitherto spray dried, but offers considerable scope for improving the qualities of products not previously believed well adapted for spray drying. It should be emphasized that the practice of our novel method is by no means limited to operations involving equipment of the type shown in the drawing. Those skilled in the art will readily appreciate how presently existing systems may be adapted to include means for developing the required sound field.

In order to illustrate the practice of our method, we have selected a preferred installation plan described in detail and shown in the accompanying drawings in which: Fig. 1 is a schematic representation of the apparatus used to carry out our novel method, and Fig. 2 is a more detailed schematic representation of the generator and its housing.

In view of the wide variations in the characteristics of materials which may be dried according to our method, we have shown in the drawing only diagrammatic representations of equipment. In practice, each installation is designed accord-

ing to the demands of the material and the relation of the drying operation to other process operations and equipment. As shown, the drying and agglomerating steps are carried out in a large cylindrical steel tank 10 provided with a cover member 20 carrying an elongated housing 30 extending from the center of the cover 20 radially off to one side and provided with a depression or well 16 in the bottom of which is set a nozzle 12 connected to a conduit 14 of reduced diameter, through which the wet material is forced under pressure to the nozzle. Inasmuch as the type of nozzle used will vary considerably with the nature of the substance to be dried, we have shown it only diagrammatically; for example, it may be arranged to jet the material radially to form in effect a circular horizontal spray indicated by the broken lines 13 and radiating from the centrally disposed nozzle outwardly toward the wall of the tank 10. Surrounding the well 16 is a frusto-conical baffle 18 inclined bodily inwardly and terminating at its upper end in an outwardly directed smoothly curved flange 19 to form with the wall of the well 16 a restricted annular nozzle affording access from the housing 30 to the interior of the tank 10. Supported within the housing 30 by a suitable base 32 is a heat exchanger 34, shown schematically in broken lines.

Connected to the housing 30 is a blower 36 arranged to draw air through a filter 38 and deliver it under pressure to the heat exchanger 34. The blower and heat exchanger may be so operated that, for example, dry air at 300° F. will flow at the rate of 20,000 cubic feet per minute between the baffle 18 and the well 16 to enter the tank 10 as an annular blast surrounding the nozzle 12.

Mounted in the axis of the tank 10 and disposed a considerable distance below the nozzle 12 is a sound generator operated by an air turbine and capable of generating sound waves in the tank 10 at an acoustic intensity of preferably greater than 150 db. above zero reference level at desired frequencies. The sound generator includes a cylindrical central casing 37 divided into upper and lower chambers with a shaft 35 extending into both chambers and carrying in the upper chamber a turbine wheel 43 and in the lower chamber a hollow rotor 40 with a series of slots at its periphery and juxtaposed to stator ports 39 formed in the casing 37 and communicating with an annular exponential horn 41. A conduit 46 supplies air under pressure to both of the chambers in the casing 37. The jets used to drive the turbine wheel 43 have been omitted for sake of clarity in the drawing but are of conventional character. The sound generator assembly is contained within a housing 44 suitably secured to the walls of the tank 10 and has frusto-conical form at its upper end as well as a conical hood 42 secured adjacent the top of the housing 44 and spaced therefrom to provide an exhaust passage for the air used to drive the turbine wheel 43; an exhaust pipe 45 leads from the upper chamber of the casing 37 into the top of the housing 44. As shown in Fig. 1 the conduit 46 is connected to a suitable compressor 48 disposed outside the tank 10. The sound generator may conveniently comprise a modified version of the generator disclosed in the copending application of C. B. Horsley et al., Ser. No. 722,240, filed January 15, 1947 for Method and Apparatus for Generating Sound Waves.

The bottom of the tank or chamber 10 comprises a wall 52 inclined to merge with the up-

per end of a wall of a second cylindrical tank 54 smaller in diameter than the tank 10, and in turn merging into a hopper 56 which may be exhausted by a valve 58 disposed at its apex. A large steel casing or housing 50, substantially pentagonal in vertical cross section, is disposed partly within the tank 10 and partly within the second tank 54, its dimensions being such that a restricted annular passage 51 is formed between the housing 50 and the top of the tank 54. The bottom of the casing 50 is open; the top of it is secured to the bottom of the generator 40. Entering through the side of the tank 54 is a large duct 62 which terminates in a vertical section 60 disposed within the casing 50. At its other end the duct 62 is connected to a cyclone separator 64 which in turn discharges through a duct 66 into a second cyclone separator 68. A stack 70 leads from the second cyclone 68 to the atmosphere and, as is usual, solids are withdrawn from the bottom of each cyclone separator. When it is desired to dry material, the blower 36 is operated to force air through the entire system thus far described, at any desired rate. The air is heated in the heat exchanger 34. The material to be dried is sprayed from the nozzle 12 at the top of the tank 10, as previously described, and the sound generator is operated to develop an intense sound field within the tank 10.

In the zone immediately surrounding the nozzle 12 the effect of the sound waves is in any case to increase the normal rate of evaporation of the moisture from the wet particles in the spray and also to cause agglomeration of the smaller wet particles, if desired, if the correct frequency is employed. In the area lying intermediate the nozzle and the bottom 52 of the tank 10, the sound waves continue to promote evaporation and optionally to cause agglomeration of dried particles. There is, of course, no sharply defined border separating the zones of wet and dry agglomeration. It is obvious that the particles reaching the lower portion of the tank 10 will be drier, generally speaking, than those momentarily at the top of the tank which have entered it relatively recently. The agglomerating effect obtained within the tank will be sufficient to build up larger particles which fall into the funnel-shaped portion 56 and can be withdrawn through the valve 58 as completely dried, solid material. Other particles will be carried into the housing 50 and through the conduit 60 to the cyclones 64 and 68. There the solid particles are separated from the air by the cyclone separators operating in conventional fashion.

It should be noted that the shape of the air inlet passage formed by the baffle 18 and the well 16 provides for smooth flow of air into the tank 10 but minimizes the dimensions of the passages through which sound can escape. It will be seen that the orifice formed for the introduction of the hot air is a nozzle in which the velocity of the entering air increases to maximum at the narrowest point with consequent drop in pressure. As the nozzle walls diverge the pressure rises and the velocity falls. Hence the air is introduced into the tank through a minimum opening but in a smooth, non-turbulent manner so that a relatively small over-all pressure drop is required, while access of the sound waves to the exterior is diminished as far as possible. The same comments apply to the channel found between the members 50 and 52.

In operating conventional driers some of the finely divided material will deposit on the walls until large masses are thus collected, clogging and fouling the drier. We have observed that in many cases suitably intense sound waves act to prevent excessive accumulation of such deposits. It would seem that the sound waves develop pressure differentials in the interstices of the deposit and, in effect, blast the particles from the wall. In the past the accumulation of such deposits has proved a great handicap; the wet solids pack on the walls in masses until the drier is completely choked and useless. Then follows the task of removing the deposits before drying can be resumed.

The apparatus shown may often be operated indefinitely without having to be shut down for cleaning. The drying of the material is accomplished more efficiently than has heretofore been possible. Finally, the operation may be not only more economical from the standpoint of power expended, but also because the fines hitherto carried off into the atmosphere in the stream of drying gas are recovered by virtue of the sonic agglomeration of particles too small to respond to ordinary separation treatment.

Having thus disclosed our invention, what we claim as new and desire to secure by Letters Patent of the United States is:

1. The method of treating a wet substance comprising injecting different sizes of particles of the wet substance into a hot gas to form an aerosol, and applying to the aerosol thus formed high intensity sound waves at an intensity of at least 150 db above 0.0002 dynes/cm.² root mean

square pressure and at a frequency of about 3.5 kc., whereby the sound waves not only promote evaporation of the moisture but also form dry agglomerates.

- 5 2. The method of treating a wet substance, comprising injecting different sizes of particles of the wet substance into a stream of hot dry gas, generating in the gas sound waves at a frequency of about 3.5 kc. and at an intensity of at least 150 db above 0.0002 dynes/cm.² root mean square pressure to impart to the particles velocities differing with the size of the particles, and then separating the substance from the gas.
